VENTILATING MECHANISM FOR TOILET BOWLS

William C. Cummings, Deadwood, S. Dak.

Application April 11, 1936, Serial No. 73,919

5 Claims. (Cl. 4—213)

This invention relates to an improved ventilating mechanism for toilet bowls. More specifically the invention embraces a mechanism in the form of an attachment capable of application to conventionally installed water closets.

It is a further object of the invention to provide the ventilating attachment in such form that it may be installed on conventional water closet bowls without change or modification of the existing installation other than the substitution of the attachment for the conventional seat and cover with which all commercial bowls are equipped.

Additionally it is a purpose and object of the invention to provide a ventilating attachment that will be economical to manufacture and install and one that will effectively and efficiently remove all objectionable odors from water closet bowls equipped with the invention.

Coming now to a detailed description of the invention from which additional advantages will be made to appear, reference will be made to the accompanying drawings wherein like references denote like parts and wherein—

Figure 1 is a plan view of the ventilating attachment taken on a plane just below the water tank of the water closet;

Figure 2 is a fragmentary view in side elevation of the attachment;

Figure 3 is a detail bottom plan view with parts broken away;

Figure 4 is a detail view showing the mounting for the attachment taken on line 4—4 of Figure 1;

Figure 5 is a further detail view showing one supporting bracket; and

Figure 6 is a diagram of the motor circuit.

Referring to the drawings, there is shown in Figure 2 a conventional water closet bowl 1 having a water tank 2 connected to the bowl through the usual connecting pipe 3. In accordance with the present invention, the usual toilet seat and seat cover, normally secured to the bowl by bolts passing through the holes 4, are removed, and the attachment of the present invention is affixed to the bowl by passing the anchor bolts 5 through the holes 4. The anchor bolts 5 specifically shown in Figure 5 are provided with openings 6 that support the pivot bearing rod 7 for the cover 8. The seat 9 is mounted in a manner to be hereinafter described. The cover 8 is provided with the pivot supporting brackets 10. The seat 9 is provided with the annularly extending channel 11 having openings 12 extending through the lower face 13 of the seat. The channel 11 connects at the rear end of the seat with the

transverse pipe member 14 rigidly secured to the seat through the medium of the bracket extension 15. The transverse pipe 14 carries a slot 16 communicating with the annular channel 11, whereby the channel 11 is in free and open communication at all times with the transverse pipe 14.

At either end of the transverse pipe 14 there is provided a socket union member 17 carried by the anchor bolts 5. These members 17 pivotally receive the ends of the pipe member 14. The socket union members 17 carry bracket arms 18 that extend back and connect with the upper ends of anchor bolts 5 as shown at 19. The arrangement is such that the seat 9 pivots in the socket members 17. The construction is shown more particularly in Figure 3. The ends of the pipe member 14 fit snugly into the socket member 17 but are free to pivot therein.

The socket members 17 have attached thereto the rearwardly extending pipes 20. These pipes 20 are connected through a telescopic union, indicated generally at 21, with the second elbow pipe 22. The pipe 22 is enlarged at the free end 23 to telescopically receive in the enlargement the free end of the pipe 20. A bushing clamp 24, threadedly carried by the enlarged end 23 of pipe 22, provides a means for securing and sealing the pipe sections 20 and 22 in any given position of adjustment.

The pipes 22 terminate in a motor housing 25. The housing 25 is provided with a suitable supporting bracket 26 for attachment to the room wall at a point below the water bowl 2 (see Figure 2). A duct member 27 is carried by the motor housing 25 and projects through the wall 28 either into the interior of a hollow partition having communication with the exterior or into any suitable stack arrangement. Mounted within the motor housing 25 is a conventional electric motor 29, on the shaft 29 of which is carried the exhaust fan 30.

The motor circuit is controlled by the seat cover 8. A control switch embracing contact members 31 and 32 (see Figure 6) is normally held by the seat cover 8 and bracket 10 in open position against the tension of the spring 33. This control switch is positioned interiorly of the pipe member 14, as shown in Figures 2 and 4. The circuit wires 34 and 35 extend from the switch through the pipe member 14 and thence back through one of the pipes 20 and the associated elbow connection 22 to connect with the motor circuit in the housing 25. Suitable detachable connections are provided adjacent the telescopic connection between pipe members 20 and 55

22. The lead wire 31 for the motor circuit extends to any suitable wall plug or other source of current.

The provision of the telescopic connections between the pipe elements 20 and 22 permits of the attachment being manufactured in a form adapted to be installed upon water closet bowls of varying specific designs and regardless of the particular spacing of the bowl from the wall. 10 Additionally it will be observed that the exhaust mechanism is so constructed that it does not in any way interfere with the plumbing connections between the bowl 1 and the water tank 2, enabling the attachment to be applied to any conventional water closet bowl with a minimum of effort and without necessitating any change or modification in the installation.

Most frame buildings have a hollow partition, and the attachment is particularly advantageous 20 for installation in such buildings since the duct 27 can be extended into the hollow partition, and openings either to the exterior or into a well ventilated attic may be provided whereby the exhaust gases are at once removed and liberated.

25 The mode of operation of the device is believed to be apparent from the foregoing description. However, it may be noted that when the toilet is not in use and the seat cover 8 is in closed position, the motor circuit is opened due to the contact of the bracket 10 with the contact member 32 of the motor circuit control switch. When the cover 8 is raised, the control switch is closed through the medium of the spring 33 which immediately cuts in the motor 28 and drives the exhaust fan 30, creating suction through the pipe connections 14, 20, and 22 directly into the channel 11 and from the channel 11 through the openings 12 into the interior of the bowl. In this manner it will be observed that there is created an extensive low pressure suction which will most effectively exhaust all obnoxious odors in a most efficient manner.

From the foregoing description it is evident that the present invention provides a very simply 45 and economically constructed attachment for water closets that can be installed with a minimum of labor and expense, and while the foregoing description is specific, it is to be understood that it is merely illustrative and that the invention 50 is comprehended by the appended claims.

Having thus described my invention, what I claim is:

1. In an attachment for a water closet bowl, a channelled seat communicating with the interior 55 of the bowl, a motor housing adapted to be mounted on and communicate with a space behind a wall located rearwardly of the bowl, pipe connections between the motor housing and seat embracing a pivotal mounting for the seat, and 60 telescopic connections in said pipe connections for adjusting the position of the motor housing in relation to the seat.

2. A water closet bowl ventilating attachment 65 adapted to be substituted for the conventional seat and cover comprising an assembly embracing a motor housing, a motor in said housing, and a motor driven fan carried thereby, a chan-

nel seat member, telescopically interconnected conduits connecting said channel seat member to said motor housing, a seat cover, and a pair of anchor bolts for securing the attachment to the bowl, said anchor bolts embracing means for independently pivotally supporting said channel seat and said cover in such manner that they move about horizontally spaced axes and with the seat support forming a part of the conduits connecting the channel of the seat to the motor housing. 10

3. A water closet bowl ventilating attachment adapted to be substituted for the conventional seat and cover comprising an assembly embracing a motor housing, a motor in said housing, 15 and a motor driven fan carried thereby, a channel seat member, telescopically interconnected conduits connecting said channel seat member to said motor housing, a seat cover, a pair of anchor bolts for securing the attachment to the bowl, 20 said anchor bolts embracing means for independently pivotally supporting said channel seat and said cover in such manner that they move about horizontally spaced axes and with the seat support forming a part of the conduits connect- 25 ing the channel of the seat to the motor housing, and a circuit for said motor including a switch adapted to be held open when said seat cover is in closed position and adapted to be closed when said seat cover is moved to open position. 30

4. A water closet bowl ventilating attachment adapted to be substituted for the conventional seat and cover comprising an assembly embracing a motor housing, a motor in said housing, and a motor driven fan carried thereby, a channel 35 seat member, telescopically interconnected conduits connecting said channel seat member to said motor housing, a seat cover, and a pair of anchor bolts for securing the attachment to the bowl, said anchor bolts embracing means for 40 independently pivotally supporting said channel seat and said cover in such manner that they move about horizontally spaced axes and with the seat support forming a part of the conduits connecting the channel of the seat to the motor 45 housing, and said telescopically interconnected conduits permitting limited lateral adjustment of said motor housing with respect to said channel seat.

5. A water closet bowl ventilating attachment 50 adapted to be substituted for the conventional seat and cover, comprising a hollow seat having its bore communicating with the closet bowl and provided with a discharge opening at the rear edge of the seat, a transverse pipe section communicating with said discharge opening and fastened to the seat to form a pivotal support for the latter, a pair of anchor bolts embracing socket members for pivotally receiving the ends of the transverse pipe section and pivot pin receiving 55 openings, a cover for said seat having a pivot pin journaled in said pin openings, a motor housing, 60 a motor and fan mounted in said housing, and conduits connecting said anchor bolt bracket members and the motor housing. 65

WILLIAM C. CUMMINGS.
